[57] CLAIM

The ornamental design of a upright panel support bracket for table, as shown and described.

DESCRIPTION

FIG. 1 is a perspective view of an upright panel support bracket for table showing my design;

FIG. 2 is a left-side elevational view thereof, the right-side elevational view being identical thereto, and the rear edge of a table top and a vertically supported rear panel being shown in dotted lines;

FIG. 3 is a front elevational view thereof;

FIG. 4 is a rear elevational view thereof;

FIG. 5 is a top view thereof; and,

FIG. 6 is a bottom view thereof;

FIG. 7 is a reduced, environmental perspective view.

The broken lines showing of a panel for a desk in FIG. 1 and of a desk in FIG. 7 are for environmental purposes only and form no part of the claimed design.
